ELECTROLYTIC APPARATUS

Vincent A. Rayburn, Baltimore, Md., assignor to
Western Electric Company, Incorporated, New
York, N. Y., a corporation of New York

Application February 10, 1943, Serial No. 475,379

7 Claims. (Cl. 204—209)

This invention relates to electrolytic apparatus, and more particularly to apparatus for the electrolytic treatment of wire.

Numerous processes have been developed for electrolytically treating wires. Among the most common treatments of this type are electrolytic cleaning processes and electroplating processes. Electrolytic cleaning processes may employ either a direct current, in which case the wire may be either the anode or the cathode, or may utilize alternating current, in which case the wire is alternately the anode and the cathode. In electroplating processes a direct current is used and the wire is the cathode. In all of these types of processes it is necessary to supply current to the wire being treated and this is usually accomplished by advancing the wire over a stationary or rotating contact member of suitable design.

Previously, the electrical contact members used have been either of the roll or the brush type, both of which have proved to have marked disadvantages. In the use of contact rolls it has been found that the surfaces contacting the wires load up with metal particles, dirt or oxide flakes, which produce current interruptions. As the wire usually moves at a high speed through a relatively short tank, any current interruptions would result in a poorly finished product. When a brush contact was used it was found that it soon became dirty, corroded, pitted, or worn out rapidly, due to the concentrated load thereon and to the abrasive action of gritty particles in the electrolytic solutions.

It has also been found advisable, in the electrolytic treatment of wire, to have wiping devices of some type to remove excess or surplus electrolyte from the wire to minimize what is known in the art as drag-out. The wipers previously used, which have usually been of the rubber or composition pads or the compressed air or gas types, have had marked disadvantages. When rubber pads were used, it was found that they soon loaded up with metal flakes, dirt, grit, etc., which abraded the wire. This type of wiper may be efficient at first, but the efficiency soon diminishes due to the wire cutting or "channeling" the pad. The air or gas type wiper takes up too much space and breaks up the liquid electrolyte clinging to the wire into a fine mist which may contaminate the ambient air with poisonous vapors unless confined under large hoods and exhausted.

The object of this invention is to provide new and effective apparatus for the electrolytic treatment of wire.

In general, the invention comprises a combined

wiper and electrical contact device having a fixed member and a pivotally mounted member, said members having wire-engaging elements associated therewith, and means to urge said pivotally mounted member toward said fixed member.

The features and advantages of the invention will become apparent from the following detailed description of a specific embodiment thereof, 10 when read in conjunction with the accompanying drawings, in which

Fig. 1 is a side elevation of combined wiper and electrical contact devices embodying the invention, having a portion thereof broken away;

15 Fig. 2 is a rear elevation of a portion of the devices looking in the direction of the arrows 2—2 in Fig. 1;

Fig. 3 is an enlarged fragmentary perspective view of an arm forming a part of one of the 20 devices;

Fig. 4 is an enlarged perspective view of an upper contact and wiper plate forming a part of one of the devices;

Fig. 5 is an enlarged perspective view of a lower 25 contact and wiper plate forming a part of one of the devices, and

Fig. 6 is a fragmentary, horizontal section taken along line 6—6 of Fig. 1.

The combined wiper and electrical contact devices embodying the invention preferably are 30 mounted in pairs so as to conserve space and for the economical handling of the wires being treated. The accompanying drawings show a pair of these devices assembled for use in connection with two wires.

Referring now to the drawings, wires 10—10 which are to be electrolytically treated pass from 35 a supply reel (not shown) through a solution tank 11 in the direction of the arrow in Fig. 1.

40 The electrolyte is continuously pumped into the tank 11 and the overflow discharges through a weir 12 at one end thereof. The wires 10—10 are also passed through the weir 12 in order that they will be submerged in the electrolyte during 45 their passage through the tank 11. The wires 10—10 pass from the tank 11 through a tank 13, wherein the tank 11 is suspended, and finally to any suitable take-up mechanism (not shown). The tank 13 collects the overflow from the tank 50 11 and the material wiped from the wire. The wires 10—10 are advanced through the electrolytic apparatus by one or more capstans (not shown) or by any other suitable means known to the art.

55 Mounted in the tank 13 on suitable electrical

insulators illustrated by an insulator 15 (Figs. 1 and 6) is a conductor bar 14. The insulator 15 is bolted to a filler plate 16 welded to the tank 13 and has metallic brackets 17 and 18 bolted to one side thereof. One end of the conductor bar 14 is secured by a bolt 19 to the brackets 17 and 18, and the other end of the bar 14 is supported in a similar manner, whereby the bar 14 is supported by the tank 13 but is insulated therefrom. An electrical cable 20 is connected by a lug 21 secured on the bolt 19 to the bar 14. The cable 20 leads to any suitable electrical source (not shown). A leg 15, depending from a casting 16, is secured to the conductor bar 14 by means of a bolt 17 threaded in a hole 18 in the conductor bar 14. The casting 16 is made of copper or other material which is a good electrical conductor and which possesses the necessary resistance to the corrosive action of the electrolyte. A circular recess 20, in the leg 15, acts as a seat for a washer head 21 of the bolt 17 which is positioned between the leg 15 and the wrench head of the bolt 17. The leg 15 has a slot 22 therein (Fig. 2) which allows the casting 16 to be removed from the conductor bar 14 when the bolt 17 is loosened enough for the washer head 21 to clear the recess 20.

Above the leg 15 the casting 16 is T-shaped in cross section (Fig. 2) and comprises a central reinforcing web 24 with flanges 25 and 26 at the sides thereof. Toward the top of the reinforcing web 24 are bosses 27 and 28, extending outwardly therefrom, and two arms 29 and 30 which extend laterally from the top of the reinforcing web 24. The flanges 25 and 26, bosses 27 and 28, and arms 29 and 30 are similar in every respect, and are used to support a pair of the devices embodying the invention. However, as the structure and operation of the two devices are identical, the following description has been limited to one of these devices only. Obviously, a pair of devices would operate independently in the same manner as would a single unit.

The flange 25 has a threaded hole 32 and recessed slots 33 and 34 formed therein on opposite sides thereof. A bolt 35 secures a lower contact and wiper plate 37 within the recessed slot 33.

The plate 37 is made of a corrosion resistant metal which is a suitable conductor of electricity, beryllium copper, stainless steel, Monel metal and high carbon steel having proved to be satisfactory materials for this purpose, depending upon the corrosive action of the electrolytes on the metal selected. Within the plate 37 is a slot 38 (Fig. 5) through which the bolt 35 passes to secure the plate to the flange 25. Thus, upon loosening the bolt 35 the plate 37 may be adjusted vertically, the limits of adjustment being the length of the slot 38. The plate 37 has a sloped surface 39 at one end thereof and an insert 41 is fastened, preferably by gas welding, within an opening 42 at the sloped end of the plate. The insert 41 is formed of an abrasive and corrosion resistant metal which is a suitable electrical conductor. One example of such a metal is a cobalt, chromium, tungsten, alloy which is sold under the trade name "Stellite." The insert 41 is provided at its upper end with a semi-circular notch 43 which is slightly larger than the diameter of the wire 10 that is to be engaged thereby.

A bore 44 extends through the bosses 27 and 28 and the web 24. Passing through the bore 44 is a rod 45 upon which an arm 47 having a bore 48 therethrough is pivotally mounted so as

to abut the boss 27. Lateral movement of the arm 47 is prevented by a cotter pin 49 which passes through the rod 45 near the end thereof. The upper end of the arm 47 is in the form of a handle 50 which may be employed to rotate the arm about the rod 45. A recessed slot 52 is formed in the lower part of the arm 47, into which fits an upper contact and wiper plate 53. The plate 53 is secured to the arm 47 by means of a bolt 54 which passes through a slot 55 (Fig. 4) in the plate 53 and screws into a threaded hole 56 in the arm 47. The plate 53 may be adjusted vertically by loosening the bolt 54 and moving the plate within the limits of the length of the slot 55.

The plate 53 may enter the recess 34 formed in the flange 25 of the casting 16, since the width of the recess 34 is slightly greater than that of the plate 53, and the recess acts to align the upper plate 53 with the lower plate 37. A screw 58, threaded through a lug 59 extending from the arm 47 aids in securing the proper pressure of the plate on the wire 10 and maintains the plate 53 in the position to which it has been adjusted, by acting against any pressure exerted by the wire 10 tending to force the plate upwardly.

The plate 53 (Fig. 4) has a V-shaped notch 60 in the lower end thereof, which has bevelled side surfaces 61—61. The plate 53, like the plate 37, is made of a metal which is corrosion resistant and a suitable electrical conductor. An insert 63 is secured, preferably by gas welding, within an opening 64 in the lower end of the upper plate. The insert 63 is made of a metal like that employed to make the insert 41, which is a suitable conductor of electricity and is resistant to abrasion and corrosion. The insert 63 has a semi-circular notch 65 formed in the lower end thereof which is slightly larger than the diameter of the wire 10.

The arm 29, extending laterally from the top of the reinforcing web 24, has a threaded hole 67 therein through which passes a threaded bolt 68. The bolt 68 is engaged by a heat and corrosion resistant spring 69 having a funnel-shaped end which fits over an enlarged cone-shaped head 70 on the bolt. The opposite end of the spring 69 is secured to the adjacent lug 59 by passing through a hole 71 formed therein. The bolt 68 is threaded into the hole 67 to adjust the spring 69 to the correct tension and is then locked in place by a nut 72 threaded onto the bolt 68 on the side of the arm 29 away from the spring 69.

The operation of the apparatus is as follows: The wire 10 is unwound from a supply reel (not shown) and passed through the tank 11 in which an electrolytic solution is maintained at a sufficient depth to cover the wire. The wire 10 leaves the tank 11 through the weir 12 and passes on through the tank 13 to the contact and wiper device embodying the invention. The handle 50 is moved in a clockwise direction, as seen in Fig. 1, thus pivoting the arm 47 on the rod 45 against the tension of the spring 69. The upper contact and wiper plate 53, which is secured to the arm 47 by the bolt 54, is thereby moved away from the lower contact and wiper plate 37. Thus, the wire 10 may be passed between the upper and lower contact and wiper plates to any suitable take-up mechanism (not shown).

When the handle 50 is released, the tension of the spring 69 will cause the arm 47 to pivot on the rod 45 in a counterclockwise direction, as seen

in Fig. 1. The upper plate 53, which is being urged towards the lower plate 37, will enter the recess 34 in the flange 25, whereby the wire-engaging notches 43 and 65 are aligned vertically.

The bolt 35, passing through the slot 38 in the lower plate 37, is loosened and the plate 37 is adjusted vertically until the wire 10 enters the notch 43 in the insert 41. The lower plate 37 is then raised a further slight amount so that the wire will be raised approximately $\frac{1}{16}$ of an inch. The bolt 54, passing through the slot 55 in the upper plate 53, is then loosened and the plate 53 is moved downwardly until the wire 10 enters within the notch 65 in the insert 63. The screw 58 is then tightened until the end thereof abuts against the top end of the plate 53.

In the event that the upper plate 53 has not been moved downwardly far enough, the wire 10 will remain wet after it has passed between the plates 37 and 53. If the upper plate 53 has been adjusted too far downwardly the wire 10 will be scraped as it passes between the plates. Thus, it is possible to determine from an examination of the wire as it leaves the plates 37 and 53 whether the upper plate 53 has been correctly positioned with respect to the lower plate 37 and the wire 10.

The notches 43 and 65 are just slightly larger than the diameter of the wire 10 and any knot or kink in the wire would be unable to pass between the said notches in the normal position of the device. If a knot occurs in the wire 10 it will first contact the slope surface 39 of the lower plate 37, whereby the wire 10 would be forced upwardly out of the notch 43 and the knot would thus be able to pass the lower plate 37. The wire 10 then forces the knot against the notch 65 in the insert 63 of the upper plate 53, the resulting pressure tending to move the upper plate away from the lower plate 37. Since the upper plate 53 is secured to the rotatably mounted arm 47, such pressure by the knot upon said plate causes the arm 47 to pivot on the rod 45 in a clockwise direction, as seen in Fig. 1, and thereby creates a clearance between the two plates. The knot on the wire 10 may thus move out of the notch 65 in the insert 63 and slide down the bevelled surfaces 61—61 of the plate 53 and so pass through the V-shaped notch 60, thus preventing any break in the wire.

The tension of the spring 69, which must be made of a heat and corrosion resistant metal because it may be subjected to high temperatures and the corrosive action of the electrolytic solution within the tank 11, is adjusted by threading the bolt 68 into the hole 67 the correct amount and then locking the bolt in place by means of the nut 72. Normally, the spring is adjusted to a tension sufficient to pivot the arm 47 in a counterclockwise direction, as seen in Fig. 1, and to cause the upper contact and wiper plate 53 to assume a position against the lower contact and wiper plate 37.

As the wire 10 passes through the notches 43 and 65, the diameters of which are barely larger than the diameter of the wire, the sides of the notches will tend to wipe off any excess solution, dirt, loosened scale or oxides that may be on the wire. The moisture, dirt, etc., will not pass beyond the plates 37 and 53 but will drop down into the tank 13. The solution removed from the wire is collected in the tank 13, and after having been filtered, is later recirculated through the solution tank 11. Thus, the plates 37 and 53 act not only to remove the dirt, loosened scale

and oxides from the wire and to supply current to the wire, but also act to conserve the amount of electrolytic solution used in the electrolytic treatment.

The casting 16, plates 37 and 53, and inserts 41 and 63 are all made of a metal having a suitable electrical conductivity and an electrical contact is made with the wire 10 as it passes through the notches in the inserts 41 and 63. The electric current is carried from the conductor bar 14 through the flange 25 of the casting 16 and through the lower plate 37 to the insert 41 therein. The electric current is carried to the insert 63 by means of the web 24, the boss 27, the rod 45, the rotatably mounted arm 47 and the upper plate 53. Since the wire 10 is wet when it engages the inserts 41 and 63, a good electrical contact is always assured.

If a dry contact is made between a contact member and a wire, sparking frequently occurs, which results in pitting of the wire and interference with the electrolytic action. The use of a wet contact prevents sparking and the accompanying undesirable results thereof.

The contact and wiper plates 37 and 53 do not, by themselves, mechanically wipe the wire entirely dry but leave a thin layer of electrolyte thereon. When an aqueous electrolyte is used, the heat generated by the passage of current from the inserts in the plates to the wire "flashes off" the moisture from this thin layer of electrolyte. Thus, the wire is both clean and dry as it leaves the combined wiper and electrical contact device.

The wire passing through the notches 43 and 65 tends to keep those surfaces of the inserts in a polished state. Also, small grains of dirt or impurities which are wiped from the wire act as an abrasive upon the said inserts, which tends to keep them in a bright, shiny condition. This, of course, assures a better electrical contact.

The advantages of using a combined wiper and electrical contact device in the electrolytic treatment of wire are that it saves space, that it provides a wet, and consequently a good, contact, and that the surfaces of the contacts are polished by extraneous grit and dirt in the electrolyte, which act as an abrasive and keep the contact surfaces clean. Also, the wiper will not load up with material removed from the wire, but the material will drain into the tank 13. Since the inserts 41 and 63 which actually contact the wire are made of a very hard, wear and corrosion resistant material, they will have a long life. These inserts, being secured within the plates 37 and 53, are replaceable.

It is obvious that the above mentioned apparatus may be modified to suit varying conditions and processes without changing its purpose or effectiveness and without departing from the invention. If desired, a plurality of units like those described hereinabove may be employed in a given electrolytic apparatus to permit a number of wires to be treated simultaneously.

What is claimed is:

1. In an apparatus for the electrolytic treatment of wire, an electrical conductor bar, a casting supported by said conductor bar, a fixed arm extending upwardly from said casting having two recesses therein on opposite sides thereof, a plate secured in one of said recesses, a wire-engaging insert mounted in said plate, an arm pivotally mounted on said casting having a recess therein, a plate secured within said recess, a wire-engaging insert mounted in said plate, means to adjust

the relative positions of said plates, and a spring to urge said pivotally mounted arm toward said fixed arm thereby causing the plate secured to the pivotally mounted arm to enter within the recess in said fixed arm not occupied by the plate to align said wire-engaging inserts.

2. In an apparatus for the electrolytic treatment of wire, an electrical conductor bar, a fixed arm secured to said conductor bar having two recesses therein on opposite sides thereof, a wire-engaging plate secured within one of said recesses, a pivotally mounted arm having a recess therein, a wire-engaging plate secured within said last mentioned recess, means to adjust the relative positions of said plates, and means urging said pivotally mounted arm toward said fixed arm thereby causing the plate secured to said pivotally mounted arm to enter within the recess in said fixed arm not occupied by the plate whereby said plates are aligned.

3. In an apparatus for the electrolytic treatment of wire, means for wiping and supplying electrical current to wire comprising a conductor bar, means for impressing an electrical potential upon the conductor bar, a support mounted on the conductor bar, a contactor secured to the support, a lever pivotally mounted on the support, and a second contactor secured to the lever and cooperating with the first-mentioned contactor to wipe the wire and supply an electrical current thereto.

4. In an apparatus for electrolytic treatment of wire including an electroplating tank for holding an electrolyte, means for wiping excess electrolyte from a wire drawn from the tank and for supplying an electric current to the wire, which comprises a conductor bar positioned near the exit end of the tank, means for impressing an electrical potential upon the conductor bar, a support secured to the conductor bar, a contactor fixed to the support, a member pivotally mounted on the support, a second contactor carried by the pivotally mounted member, said contactors having complementary semicircular cut-out portions for closely retaining therein a wire emerging from the tank to wipe the wire and to supply an electric current thereto, and a spring for normally retaining the contactors in a cooperative relationship.

5. In an apparatus for electrolytic treatment of wire, a contacting device comprising a conductor bar, a support mounted on the conductor bar, a contactor having a semicircular cut-out portion fixed to the support, a lever pivotally mounted on the support, a second contactor having a semicircular cut-out portion complementary to the first mentioned cut-out portion secured to the lever, a spring secured to the support and to the lever to urge the contactors together, and means for aligning the contactors whereby the contactors will wipe and supply an electrical current to a wire advanced through the circular opening formed by the complementary semicircular cut-out portions.

6. In an apparatus for electrolytic treatment of wire, a contacting device comprising a conductor bar, a support mounted on the conductor bar and having a recess formed therein, a fixed contactor secured to the support and having a semicircular cut-out portion, a lever pivotally mounted on the support, a second contactor secured to the lever and having a semicircular cut-out portion complementary to the first mentioned cut-out portion, and a spring secured to the lever and to the support for urging the second contactor into the recess whereby the contactors are aligned so that the complementary cut-out portions form a circular aperture through which a wire may be drawn, said contactors engaging the wire around the entire periphery thereof for wiping the wire and supplying an electrical current thereto.

7. In an apparatus for electrolytic treatment of wire, a contacting device comprising a conductor bar, means for impressing an electrical potential upon the conductor bar, a metallic support adjustably secured to the conductor bar, a plurality of electroconductive contactors secured to the support for wiping and supplying an electrical current to an equal number of wires, a plurality of metallic levers pivotally mounted on the support, a plurality of electroconductive contactors secured to the levers for cooperating with the first mentioned contactors, and a plurality of springs for urging the levers toward the support.

VINCENT A. RAYBURN.
